US0D1015750S

(12) **United States Design Patent** (10) **Patent No.:** **US D1,015,750 S**
(45) **Date of Patent:** **** Feb. 27, 2024**

(54) **ORAL CARE DEVICE**

(71) Applicant: **Sage Products, LLC**, Cary, IL (US)

(72) Inventors: **Paul Michael Fowler**, Rockford, IL (US); **Ronald C. Cagle**, Crystal Lake, IL (US); **Theresa L. Sebastian**, Cary, IL (US); **Timothy J. Rapinchuk**, Cary, IL (US)

(73) Assignee: **Sage Products, LLC**, Cary, IL (US)

(**) Term: **15 Years**

(21) Appl. No.: **29/827,318**

(22) Filed: **Feb. 18, 2022**

Related U.S. Application Data

(60) Continuation of application No. 29/759,473, filed on Nov. 23, 2020, now Pat. No. Des. 944,016, which is (Continued)

(57) **CLAIM**

We claim the ornamental design for an oral care device, as shown and described.

DESCRIPTION

FIG. 1 is a top, front, perspective view of the claimed design of an oral care device, according to an embodiment; FIG. 2 is a right end view of the claimed design of FIG. 1. FIG. 3 is a left end view of the claimed design of FIG. 1; FIG. 4 is a front view of the claimed design of FIG. 1; FIG. 5 is a rear view of the claimed design of FIG. 1; FIG. 6 is a top view of the claimed design of FIG. 1; FIG. 7 is a bottom view of the claimed design of FIG. 1; and, FIG. 8 is a bottom, rear, perspective view of the claimed design of FIG. 1.

The broken lines in the drawings illustrate environmental structure and form no part of the claimed design.

1 Claim, 4 Drawing Sheets
